DESIGN FOR A WOMAN'S SHOE OR SIMILAR ARTICLE

Hyman E. Zacken, Montreal, Quebec, Canada

Application January 14, 1942, Serial No. 105,194
In Canada October 9, 1941

Term of patent 3½ years

To all whom it may concern:

Be it known that Hyman E. Zacken, a subject of Great Britain and resident of Montreal, Province of Quebec, Canada, has invented a new, original, and ornamental Design for a Woman's Shoe or Similar Article, of which the following is a specification, reference being had to the accompanying drawing, forming part thereof, in which

Fig. 1 is a top plan view of a woman's shoe embodying my new design

Fig. 2 is a side elevational view thereof; and
Fig. 3 is a bottom plan view thereof.

I claim:

The ornamental design for a woman's shoe or similar article, substantially as shown.

HYMAN E. ZACKON.
